RADIO ANTENNA FOR AUTOMOBILES

Joseph H. Cohen, Bridgeport, Conn., assignor to
Casco Products Corporation, Bridgeport, Conn.,
a corporation of Connecticut

Application March 25, 1937, Serial No. 132,991

6 Claims. (Cl. 250—33)

This invention relates to radio antennas, and, more particularly, aims to provide a novel and valuable radio antenna to be carried by an automobile.

The installation of radio-receiving sets in automobiles is becoming more and more widespread, and a problem has been to obtain a convenient and practicable mounting for the antenna on the exterior of the automobile.

By the present invention an antenna is provided which may be carried on the exterior of the vehicle, yet will not detract from the appearance of the car or give the same an undesirable or unusual appearance. As the invention is preferably carried out, the antenna is carried by a fender of the car, preferably as part of a fender guide.

A feature of the invention, therefore, is the provision of a single attachment which is so constructed that it is a combined fender guide and radio antenna, and in which, preferably, the staff of the fender guide constitutes the antenna.

The staff of a fender guide is usually a hollow metal tube, to obtain rigidity with light weight, and often to allow for passage, through the tube, of an insulated current supply wire leading to one terminal of an illuminating bulb in a hollow target at the top of the fender guide. Where the guide has a target which is thus to be illuminated, the other terminal of the bulb is usually grounded through the staff and through a metal clamping means by which the guide is secured to the fender. But with the staff grounded, it cannot act as an antenna.

Another feature of the invention is the provision of a combination of parts such that the difficulty just referred to is overcome. A now preferred arrangement for the purpose, in carrying out the invention, is one in which the staff is insulated against being grounded to the car through the clamping means, but one in which at the same time one terminal of the bulb is grounded to the car fender through the clamping means.

A feature of the invention, whether or not the fender guide has a target which is to be illuminated by a contained electric bulb, is the provision of a combined fender guide and radio antenna, in which the fender guide staff is of metal, in which this staff acts as the antenna, and in which the staff is carried by but electrically insulated from a metal clamping means for securing the fender guide to a car fender.

In a fender guide it is desirable to have the lower end of the staff universally adjustable rela-

tive to the clamping means, so that even though the clamping means may be somewhat tilted laterally or longitudinally of the automobile after its securement to a fender, the staff may then be adjusted to vertical position.

Another feature of the invention, in the above connection, is the provision of a combined fender guide and radio antenna, in which the fender guide staff is of metal, in which the staff acts as the antenna, and in which the staff, angularly adjustable relative to the metal clamping means, by way of a metal interponent between the staff and the clamping means, and which interponent is in electrically conductive relation to the clamping means, is electrically insulated from such interponent.

A further feature of the invention is the provision of a combined fender guide and radio antenna, in which the metal staff of the fender guide acts as the antenna, and in which such staff is adjustable to vary the effective length of the antenna.

In a broad aspect, the invention provides a fender-carried post-like structure so constructed that a main metal portion thereof provides an aerial for a radio receiver on the car.

Other features and advantages will be hereinafter apparent.

In the accompanying drawings:

Fig. 1 is a front elevation of a combined fender guide and radio antenna according to the invention, clamped to a fender a portion of which is shown in section.

Fig. 2 illustrates the upper portion of the embodiment of Fig. 1, on an enlarged scale and in axial section.

Fig. 3 is a view similar to Fig. 2, but showing the lower part of the device.

Fig. 4 is a side elevation of another embodiment of the invention, and one wherein the staff is telescopic in construction for variation of the effective length of the antenna.

Fig. 5 is a similar view of the device of Fig. 4, but with the telescoping sections of the staff rearranged to lower the target level, but to have it somewhat above its usual one in an ordinary fender guide when used as such.

Fig. 6 shows the device of Fig. 5 in axial section and on an enlarged scale, from a point near its top down to its means for securing it to a fender, the latter and certain parts of the securing means shown in section.

Fig. 7 is an enlarged fragmentary view, partially in axial section, showing a detail of construction of a connection between two staff sec-

tions for coupling them when adjusted to a desired telescoping relation.

The device of the present invention, in the exemplary embodiment thereof illustrated in Figs. 1 to 3, incorporates a hollow metal tube 10 which is to constitute a radio antenna as well as serve as the staff of the fender guide.

This fender guide is shown as including, as usual, in addition to the staff, a target 11 at the top of the staff, and a metal clamping means 12 at the bottom of the staff, whereby the fender guide can be secured in upright position on an automobile fender 13. The clamping means shown is described and claimed in my copending application Serial No. 94,911, filed August 8, 1936, and is now preferred, but, as will be understood, any suitable type of means for securing the fender guide properly to a fender may be employed. The securing means 12 includes an L-shaped bracket 14, a clamping plate 15, and a screw 15' for drawing these two parts together to obtain a tight and dependable grip on the fender in the manner illustrated in Fig. 1. The bracket 14 is transversely arched along its bottom horizontal limb, and also along an upstanding vertical limb to the upper end of which the lower end of the staff 10 is connected. Transverse arching of the bracket provides a vertical channel and a horizontal channel, the latter below the end of the fender bead 13a. In my copending application aforesaid, these channels were provided for the accommodation of a current supply wire for an electric light bulb in the hollow target at the top of the fender guide. In the present case, these channels are employed for the accommodation of a plurality of wires as will be later explained.

The vertical channel just referred to, marked 14a in Fig. 3, continues all the way up to the top of the vertical limb of the bracket 14, which limb at its upper end is curled around to form a split neck 16. This neck is externally threaded, so that a metal nut 17 may be tightened up on the same. The top of the neck 16 has a spherically annular seat 16a, and the nut 17 has a similar but oppositely facing seat 17a. These seats form the socket of a ball-and-socket mounting for a metal piece 18; the piece 18 carrying the ball 18a of such mounting at its lower end.

The upper end of piece 18 is externally threaded, and screwed directly thereon is the lower end of a tubular insulator 19 in the upper end of which is mounted the lower end of staff 10.

Thus the staff 10 is carried by the metal securing means 12, and the staff may be universally inclined relative to the axis of the neck 16 of the bracket 14 in order to set the staff vertical and so properly place the target after securement of the bracket to the fender, but, nevertheless, the staff is insulated against being grounded through the bracket despite the fact that the ball 18a is a metal interponent supporting the staff and in direct contact with the bracket.

The insulator 19 is shaped interiorly to provide a lower recess threaded for receiving the upper threaded portion of the metal piece 18, an upper recess threaded for having screwed therein a metal bushing 20, and an intermediate bore of a diameter matching that of a bore running through the metal piece 18 from top to bottom of the latter. The bushing 20 is internally threaded, and the lower end of the staff 10 is externally threaded, so that after screwing the bushing tight into the insulator, the lower end

of the staff may be screwed tight into the bushing. In order to strengthen and dress up the insulator, and also to increase the capacitive effect of the antenna, the insulator is shown as enclosed within a metal shell 21 metallically connected to the staff by way of the bushing 20.

The target 11 is shown as of the knob type, and includes a main metal housing 22, of sleeve form, providing an upper chamber 22a and below this chamber a bore 22b matching the outside diameter of the staff 10. At the bottom of the chamber 22 is an annular wall 22a', and the top of the chamber is enlarged above an annular swell 22c. Fitted within the chamber 22a is an insulator sleeve 23, and within the latter is a metal socket 24 threaded for the mounting therein of the base 25a of an electric bulb 25. This bulb is for illuminating the desired part of the target, and such part is here shown as comprising a dome 26a forming the top portion of a cap 26 of translucent material. Dome 26a is integrally carried at the top of a central hollow sleeve 26b internally threaded to take an external thread on the upper end of housing 22. An upwardly flaring conical metal skirt 27 limits the illuminable area of the target to that of dome 26a, the upper end of the skirt being set in a groove running around the periphery of the dome and the lower end of the skirt being flanged in under the sleeve 26b. The housing thread which takes the cap 26, also takes a nut 28, so that when the cap has been screwed well down on the housing 22, with the nut 28 all the way down on the housing, the nut may be screwed up to lock the cap securely in place.

While the target 11 may be secured to the upper end of the staff 10 in any suitable way, such securing means is shown in the present case as including a nib-screw 11a.

The contact in the socket 24 for the central terminal of the bulb is shown as of conventional type, being the upper end of a coil spring 29 positioned in a block 30 of insulation in the bottom of socket 24. The lower and larger end of this spring rests in a recess in the top of the block 30, and below this recess the block has a shouldered bore as illustrated overlying an opening 24a in the socket bottom.

To the lower end of the spring 29 is connected, as by soldering, the bared end of an insulated wire 31, this wire-end fitting in the upper or smaller diametered part of the shouldered bore of block 30, and an end length of the insulation 31a of the wire fitting in the lower and larger part of such bore. The wire 31 and its insulation 31a continue down through the opening 24a and the chamber 22a, and thence all the way down through the hollow staff 10, the insulator-chamber 19a, the metal piece 18 and the channel 15 of the bracket 14, and thence under the bead 13a of the fender, for extension to connection with a current source on the automobile.

According to the invention, as the same is illustrated in the embodiment now being described, the circuit for the bulb 25 beyond the socket 24 which contacts the other terminal of the lamp base, is completed down through the fender guide, but, at the same time, the staff 10 is insulated against grounding so that it can be employed as a radio antenna. This result is here accomplished by providing an insulated wire 32 leading from the socket 24 down through the staff 10 and thence through the central bore of insulator 19, to the metal piece 18 forming part

of the ball-and-socket mounting for the staff at the upper end of the bracket 14.

The insulation 32a of the wire 32 completely covers the latter except close to its opposite ends, where the wire 32 is bared only enough to allow the upper wire-end to be soldered to the socket 24 and the lower wire-end to be gripped in a familiar type of eyelet-clip 33.

Thus, as shown, at the upper end of the wire 32 the insulation 32a extends high enough to prevent contact of the wire with the staff 10, and at the lower end of this wire its insulation extends down far enough to prevent contact of the wire with the staff. While the upper end of the wire 32 is connected to the socket 24, the socket is completely insulated from the housing 22, and hence from the staff, by the insulator sleeve 23. At the lower end of the wire 32 its insulation extends well down within the central bore of the insulator 19.

It will be noted that by these arrangements the staff 20 is completely insulated at its upper end. And, as already stated, the staff at its lower end is prevented by the insulator 19 from being grounded to the bracket 14. At the same time, however, the bulb 25, through the socket 24 and the wire 32, is grounded to the bracket.

In order to make proper connection of the staff 10 as an antenna, to a radio receiver on the car, an insulated wire 34 is provided which runs down through the central bore of the insulator 19, then through the metal piece 18 into the channel 15 of the bracket 14, and then under the bead 13a of the fender for extension to the radio receiver. The insulation 34a of this wire covers the latter completely except close to the upper end of the wire, where bared only sufficiently to allow it to be gripped in an eyelet-clip 35.

As shown in Fig. 3, the wires 32 and 34, where they pass each other, are separated by the insulation of both, and there is no chance of the staff 10 being accidentally grounded through contact of these two wires.

In assembling the embodiment shown in Figs. 1 to 3, care should be taken that the insulation of wires 31, 32 and 34 extend close to the bared ends of the wires where connected to the fender guide parts, to hold each wire to its appointed function as above described. It is important in this connection to have the wire 32 of such length that when the parts are finally assembled, as illustrated, there will be no slack in this wire such as will allow it to touch a part of either of the other two wires when they are extended through the fender guide.

The embodiment now being described may be assembled to avoid undesirable slack in the wire 32, as will now be described.

The bared ends of the wires 32 and 34, after the wire 32 has been precut to the proper length, are coiled around within the annular channels of the eyelet-clips 33 and 35, and these clips are axially compressed so as securely to seize the wire coils. The main length of the wires are then bent perpendicular to the flat of the eyelets, and so that the wires nowhere extend beyond the peripheral limits of the eyelets, this being permitted by a notch (not shown) in the appropriate eyelet flange.

As the next step, the parts of the device shown in Fig. 3 are first assembled. Before any of the parts shown in Fig. 3 as above the metal piece 18 are added, the wires 31 and 34 are passed through the bore of the piece 18. Since the wire 34 should

have its end gripped by the eyelet-clip 34 uppermost, this wire is sent down through the piece 18, but after the wire has been sent down through the central bore of the as yet unconnected insulator 19. Next, the wire 32 is drawn up through this insulator, with its end gripped by the eyelet-clip 33 lowermost, until the clip 33 is drawn up into the lower recess in the insulator as illustrated. The insulator is then screwed up tight on the upper end of the piece 18, thus clamping the eyelet-clip 33 in place. Next, the wire 34 is pulled down to draw the eyelet-clip 35, on the upper end of that wire, into the bottom of the upper recess in the insulator 19, thus clamping the eyelet-clip 35 in place. After this, the bushing 20 is screwed tight in the upper end of the insulator. The wires 31 and 32 are then passed through the as yet unconnected staff 10, and the staff is screwed up tight in the bushing.

The parts next to be assembled are those shown at the upper portion of Fig. 2.

With the housing 22 disconnected from the staff 10, and with the cap 26 disconnected from the housing, and with the bulb 25 not yet in place, a workable length of the wire 31 is drawn up above the top of the staff, and the upper end of this wire is bared to a length slightly greater than that of the upper reduced portion of the bore in the lower part of insulation block 30. This bared wire length is sent up into the block bore, so that a length of insulation 31a fills the lower larger part of the bore as shown, and then the upper end of the bared wire length is soldered to the lower end of the spring 29. Next, with the nib-screw 11a retracted to the necessary extent, the housing 22 is placed on the upper end of the staff, and slipped down along the same until the top of the housing is brought down at least as low as the top of the staff. The housing may be dropped down the staff all the way to the bushing 20, or it may be temporarily set at any desired position by tightening up the nib-screw 11a. As a result of this downward movement of the housing, and with it the insulator sleeve 23, which latter is fitted more tightly in the housing than around the socket 24, the socket will be left exposed. As thus exposed, the socket will be elevated as in Fig. 2. With the socket thus exposed and elevated, soldering of the upper end of the wire 32 to the bottom of the socket, as shown in Fig. 2, is easily done, despite the fact that the wire 32 is of a length such that it is to have no appreciable slack in the finished device.

When, now, the housing 22 is pushed along the staff, to the location illustrated, so that the nib of the screw 11a may be advanced by turning of the screw into the most convenient one of several nib holes 11b provided in the upper end of the staff, all the parts of Fig. 2 will automatically become finally assembled as there shown. During the upward movement of the housing to the position of Fig. 2, the insulator sleeve 23 moves up relative to the socket 24 until a shoulder in the sleeve engages the bottom of the thread of the socket as illustrated. The shoulder last referred to is the inside face of an annular swell of the sleeve substantially opposite the annular swell 22c of the housing 22. There is some play shown between these swells, but this is merely to facilitate initial assembly of the insulator sleeve within the housing while allowing for slight variations of shape between different sleeves.

The swell in the insulator sleeve 23 is so located along the length of the latter, and relative to the

distance between the bottom of the thread of the socket 24 and the bottom of the socket, that, when the operations above described have been completed and the nib-screw 11a is tightened up to finally assemble the device, the wire 32, without appreciable slack, will be housed in the fender guide and connected to interior parts thereof as intended.

Referring to the embodiment of the invention illustrated in Figs. 4 to 7, there is shown a fender guide having a non-illuminated target 36 carried at the upper end of the top section of a three-section telescopic staff 37.

As shown, the bottom tubular section 38 is mounted at its lower end exactly as is the staff 10 as in Figs. 1 to 3; that is, this section is screwed down into a bushing 20, which in turn is screwed down into the upper portion of an insulator 19, and this insulator is screwed to the top of a metal piece 18 which, with the nut 17 and a bracket 14, provides a ball-and-socket adjusting and holding means for the bottom of the staff. The bracket 14 is, as in Figs. 1 to 3, part of a securing means 12 including also a clamp plate 15 and a draft screw 15' whereby the fender guide may be mounted on an automobile fender 13.

Slidably received in the staff section 38, is another tubular staff section 39, and slidably received in the section 39 is a rod section 40, this last being the section which has suitably mounted on its top the target 36.

Fig. 1 shows each of the two upper sections as extended fully above the section therebelow, while Fig. 2 shows the top section 40 considerably but only partially extended above the section 39 and the lower section almost wholly collapsed in the bottom section 38. By variously extending and collapsing one or more of the sections relative to the others, the fender guide may be given any desired length, to vary the effective length of the staff 37 when used as a radio antenna.

The staff sections 38, 39 and 40 are of metal, in good contact where they overlap, and in the same way as in Figs. 1 to 3, the staff as a radio antenna is prevented by the insulator 19 from being grounded by way of the bracket 14 or the ball-and-socket mounting including the metal piece 18.

The means for permitting telescopic adjustment of the staff 37, and for clamping the staff in the adjustment selected, thereby to obtain good contact between the different staff sections, includes a nut 41 at the top of each of the two lower tubular sections 38 and 39. The upper end of each of these sections is longitudinally slotted, as at 42 in Fig. 7, and this slot interrupts an external thread on the section for taking the nut-thread. The upper interior of the nut, above its thread, is shaped to have a conical wall 43. When an upper section is telescoped to the desired extent within a section therebelow, tightening of the nut 41 on the latter section brings the wall 43 against the top of such section and reduces the diameter thereof sufficiently to clamp the two sections tightly together, this being permitted by the slot 42.

As in Figs. 1 to 3, in order to make proper connection of staff 37 as an antenna, to a radio receiver on the car, an insulated wire 34 is provided which runs down through the central bore of the insulator 19, then through the metal piece 18 into the channel 14a of the bracket 14, and then under the bead of the fender 13 for extension to the radio receiver. The insulation 34 of

this wire covers the latter completely except close up to the upper end of the wire where bared to allow it to be gripped in the eyelet-clip 35. This clip, as in Fig. 3, is secured in the insulator 19 by the bushing 20.

Variations and modifications may be made within the scope of this invention and portions of the improvements may be used without others.

I claim:

10. 1. A combined fender guide and radio antenna comprising a metal staff adapted to carry a target near its top; a metal fender clamp; a connection between said clamp and the staff including an insulator having a socket, and a metal liner secured in said socket and within which liner is secured the lower end of the staff; and a terminal having a conductor to connect the staff as an antenna to a radio receiver, said terminal being confined in the socket by the liner.
15. 2. A combined fender guide and radio antenna comprising a metal staff adapted to carry a target near its top; a metal fender clamp; a connection between said clamp and the staff including an insulator presenting a socket, a metal bushing threaded into said socket, said bushing having an internal thread and the lower end of the staff having a coacting external thread whereby the staff may be screwed in the bushing; and an annular terminal for a conductor to connect the staff as an antenna to a radio receiver, said terminal being interposed between the bottom of the socket and the bushing.
20. 3. A device as in claim 2, in which there is a hollow target on the fender guide near the top of the staff; in which there is a mounting means for an electric lamp in the target; in which the insulator has an upwardly extending socket at its lower end; in which there is a metal member upstanding from and conductively carried by the metal fender clamp, and extended into and in threaded engagement with the socket last-mentioned; and in which there is an annular terminal for a conductor to supply current to the lamp, said terminal being confined in the socket last-mentioned by said upstanding metal member.
25. 4. A combined fender guide and antenna, comprising a supporting structure having means for securing the same to the fender of an automobile at an edge thereof, said structure including an upstanding metal member; an upstanding metal staff; means for mechanically connecting but electrically insulating the staff from said supporting structure comprising an insulator at its lower portion sleeving said member and at its upper portion sleeving the lower end of the staff; and a plurality of terminals one connected to the staff and one to said member and both housed in the insulator and insulated thereby from each other.
30. 5. A combined fender guide and antenna, comprising a supporting structure having means for securing the same to the fender of an automobile at an edge thereof, said structure including an upstanding metal member; an upstanding metal staff; means for mechanically connecting but electrically insulating the staff from said supporting structure comprising an insulator at its lower portion sleeving said member and at its upper portion sleeving the lower end of the staff; and a terminal housed within the insulator and connected to the staff.
35. 6. A combined fender guide and antenna, comprising a supporting structure having means for securing the same to the fender of an automobile

at an edge thereof, said structure including an upstanding metal member; a tubular metal staff; a hollow target near the top of the staff; means for mounting an electric bulb in the target and having terminals one insulated from the other; means for mechanically connecting but electrically insulating the staff from said supporting structure comprising an insulator at its lower portion sleeving said member and at its upper portion sleeving the lower end of the staff; a plurality of annular terminals both housed in the insulator, with one in contact with the lower end of the staff but insulated from said member, and the other in contact with said member but insulated from the staff; a wire extending from the 15

staff but insulated therefrom and joining one of the terminals of the lamp mounting and the annular terminal which is in contact with the upstanding metal member; another wire passing through the staff but insulated therefrom and from the wire first-mentioned, this wire extending from the other terminal of the lamp mounting and passing through both annular terminals but insulated therefrom, for connection to a source of current supply; and a third wire extending from the annular terminal which is in contact with the staff and passing through the other annular terminal but insulated therefrom, for connection to a radio receiver.

JOSEPH H. COHEN.
